TRAVERSING ROLL

William V. Henry, Candler, N.C., assignor to American Enka Corporation, Enka, N.C., a corporation of Delaware

Filed Nov. 7, 1956, Ser. No. 620,975

5 Claims. (Cl. 242—43.2)

This invention relates to grooved rolls for traversing yarn during the winding of a package and more particularly to improved groove surfaces more resistant to the wear caused by contact of yarn as it travels through and is guided by the groove.

In the winding of yarn into package form it is known to provide a cylindrical roller with an endless helical cam groove in the outer surface thereof, to pass the running yarn chordwise of the cylinder within the groove and to rotate the cylinder thereby causing traversal of the yarn along the take-up package at a speed commensurate with that of the yarn. With a traversing roll of this type the helical groove is usually provided with two portions wherein the direction of travel is rapidly reversed to prevent non-uniform winding at the ends of the take-up package. At these rapid reversal portions the yarn imparts a concentrated sliding wear on the wall surface of the groove. In order to extend the useful life, so to speak, of the traversing roll, it has been proposed to insert a wear-resistant yarn-contacting guide pin at the aforesaid reversal portions of the helical groove. A recent example of this is shown in U.S. Patent No. 2,736,506, dated February 28, 1956.

Although the guide pins of the aforesaid patent obviate to a large extent wear caused by sliding of the yarn over that portion of the groove wall, it has now been found that an even more concentrated wear occurs at other areas along the groove which areas heretofore were not protected by guide pins or any other means. For example, both a sliding and a rubbing action between the yarn and cam groove occur along the bottom surface at the rapid reversal portions and along certain outer edges of the groove, whereas the yarn never contacts and therefore wear rarely occurs along the walls of the groove except at the reversal portions thereof. The reason for this is that the yarn is continuously shifted laterally although there is a momentary dwell at the end of each traverse stroke.

When the traversing roll is used with a high speed nylon winding machine, one operating upwardly of 900 meters per minute, for example, the aforementioned sliding and rubbing action of the yarn on the cam groove presents a very serious maintenance problem. With a standard traversing roll die cast from aluminum it has been found that yarn, and especially nylon, actually cuts or saws into certain surfaces of the groove within a period of 12-15 weeks of continuous use. Since such a roughened surface is harmful to the yarn, producing ruptures or breaks in the outer filaments thereof, the worn traversing roll must be repaired or replaced at the first signs of wear. In view of the serious nature of the problem a number of techniques have been devised in order to overcome excessive groove wear.

It has been suggested, for example, that the surfaces of the groove be chrome plated. Although such an operation has advantages from a theoretical standpoint, it has the disadvantage of being expensive in initial preparation and also in maintenance. Even though a plated

groove generally will last longer than one which is unplated, wear eventually will occur, and when this happens the groove must first be smoothed and then again plated. Moreover, die cast aluminum cannot be finished to desired surface smoothness and such a surface, even chrome plated, is difficult to polish to the necessary degree for yarn guiding purposes.

It has been suggested, further, to mount cast iron plates along portions of the groove wherein wear is more likely to occur. Such plates have not proven very satisfactory, however, for the reason that the yarn does not thread up as well as when using conventional traversing rolls. Moreover, the plates project outwardly of the rapidly rotating roll and therefore are dangerous, especially to an operator who must keep the surface of the roll clean even when the same is in operation.

One of the objects of the present invention is to provide an improved traversing roll not having inherent disadvantages such as discussed above.

20 Another object of this invention is to provide a traversing roll having improved wear-resistant qualities.

Still another object of the present invention is to provide a traversing roll having wear-resistant yarn-contacting members disposed at strategic points along the surface of the cam groove.

In accordance with the present invention the helical cam groove of a yarn traversing roll is channeled along the outer edges thereof which are contacted by the running yarn and a wear-resistant guide wire is affixed within these channels. Moreover, in the preferred embodiment of this invention, the helical cam groove is provided with both radial and axial guide pins at each of the rapid reversal sections. This provides substantially flush wear-resistant yarn-contacting surfaces which are inexpensive to manufacture and which are easy to install as well as to replace when such is found to be necessary or desirable.

Other objects and further advantages of the present invention will become apparent upon consideration of the following detailed description of a preferred embodiment thereof in conjunction with the accompanying drawings; wherein

Figure 1 is a view in elevation showing one specific use of a traversing roll constructed in accordance with the present teachings;

Figure 2 is an elevation view of one of the traversing cams shown in Figure 1 and showing also the location of applicant's wear-resistant yarn-contacting members;

Figure 3 is a sectional view taken along the line 3—3 of Figure 2 and showing the manner in which the guide wire is secured within the channel;

Figure 4 is a sectional view taken along the line 4—4 of Figure 2 and showing in detail the relationship between the guide pins, guide wire and groove at one of the rapid reversal sections; and

Figure 5 is an elevation view of the wear-resistant guide wire used along the outer edge of the cam groove.

One instance wherein applicant's improved traversing roll has particularly advantageous use is in the high speed winding of nylon yarn immediately after the same is formed by a melt-spinning apparatus, which, on the average, approximates 900 meters per minute. In Figure 1 of the drawings a pair of traversing rolls designated generally by reference numeral 10 is shown in such a typical use. The yarns 11 are fed from a melt-spinning apparatus (not shown) in the direction indicated by the arrows to a surface-driven take-up spool 12. Since the drive means for the roller 10 and spool 12 is known and forms no part of the present invention the same has not been illustrated. Each yarn passes chordwise through a helical groove 13 formed in the surface of each roller 10. As the roller rotates, it is apparent that

the yarn is vibrated laterally along the surface of take-up spool 12 to form a package. Two of these packages are shown inasmuch as the rollers 10 are usually mounted in tandem. Since these rollers are identical, further discussion will be limited to one of the two shown in Figure 1.

For a more detailed explanation of the present invention, attention is directed to Figures 2, 3 and 4 of the drawing. In Figure 2 it can be seen that the helical groove 13 extends completely around the outer surface of roller 10 in order to form a composite guide surface for continuously traversing yarn along the surface of the take-up package. It is evident from the drawings that one side of the groove functions to traverse the yarn in one direction and the opposite side traverses the yarn in the opposite direction. The helical groove 13, as shown, is provided with two quick reversal portions 14 in order to prevent excessive build-up of the yarn layers at the respective ends of the take-up package. As pointed out hereinabove, it has now been found that wear occurs not only along the vertical wall of the groove at these rapid reversal portions but also along the bottom thereof. Moreover, when using only the radial pin suggested in said U.S. Patent No. 2,736,506, it has been found that concentrated wear occurs along the bottom surface of the groove immediately adjacent to the radial pin.

In accordance with the present teachings, a wear-resistant radial guide pin 15 is mounted so as to project slightly outside the surface of groove wall 16 at the high point of each of the rapid reversal sections, as shown in Figure 2. The disposition of pin 15 is such that the yarn 11 is maintained free from contact with the wall 16. In order to mount this pin, a radially extending channel is cut or otherwise formed in the surface of the wall, after which the pin 15 is inserted therein and locked into position by means to be described hereinafter.

In cooperation with each of the radial pins 15, it has been found expedient to mount a wear-resistant axial guide pin 17 in and projecting slightly outwardly of the bottom surface 18 of groove 13 at each of the reversal portions 14. These pins 17 may be mounted in a manner similar to that discussed above in connection with pins 15, and serve the purpose of maintaining the yarn 11 free from contact with the bottom surface 18. Usually the aperture through which the pins 17 are mounted is closed by known plug means to prevent accidental dislocation of the pins therefrom. It has been found that pins 17 function more effectively if placed adjacent the radial pins and on the leading or forward side thereof relative to the direction of rotation of traverse roller 10, as indicated by the arrow in Figure 2.

While the aforementioned axial and radial pins serve to eliminate wear occasioned along the wall and bottom surface of groove 13, it has been found that even a more pronounced sliding and rubbing action resulting in wear occurs along certain outer edges of the groove. As mentioned previously herein, at any given instance, only one wall of groove 13 functions to shift the yarn laterally for winding purposes. Thus, certain areas of the groove rarely, if ever, come into contact with the yarn and wear along the surface of the groove at these areas is inconsequential. With respect to the yarn contacting surfaces, however, concentrated wear detrimental to the usefulness of the traverse roller has been found to exist and novel means is provided herein to overcome this problem.

Along the outer edge of the effective yarn traversing surface of the groove wall 16 there is mounted a wear-resistant guide wire 20. It has been found that chrome plated steel is particularly adaptable for such use. Any other suitable wear-resistant wire could of course be used. In order to condition the roller 10 for reception of guide wire 20, a channel is formed, by machining, die casting or any other suitable means, along the outer edge of wall 16, said channel having overlapping lip portions

21 and 22 between which the wire 20 may be pressed. Communicating with each end of the channel is an oblique aperture (not shown) through which the ends 23 of wire 20 may be projected, after which these ends are struck over or bent as shown by dotted lines in Figure 5, this action drawing the wire snugly into the channel. The roller 10 is hollow, with suitable supporting webs, which permits access of a hammer or other suitable instrument for striking over the projecting ends of wire 20 into the dotted line position shown. If desired, the wire 20 may also be cemented into the channel provided therefor. It has been found that cement from the epoxy or epon class operates quite well for this purpose.

While the immediately preceding description concerned mounting of guide 20 in the outer edge of wall 16, it is apparent that it is equally applicable to mounting of the guide wire along the outer edge of wall 24 inasmuch as the technique is the same in each operation.

As evidenced by Figure 3, the guide wire 20 projects slightly above the plane surface of the groove wall 24. This reduces contact between the yarn and wall and therefore prevents excessive wear. Inasmuch as the yarn is passed chordwise through the groove (see Figure 1), the most concentrated wear occurs along the outer edges heretofore mentioned, whereas wear along the walls of the groove, with the exception of the rapid reversal portions, is distributed over a much wider area and, insofar as can be determined, is not critical.

Each of the guide wires 20 is shown as extending approximately 180 degrees around the surface of roller 10. The wall 16 shifts the yarn to the left, as viewed in Figure 2, and has no effect on the return stroke, whereas the converse is true of wall 24. Consequently, it has been found that each wire 20 need extend only from the trailing edge of one rapid reversal portion substantially through the other reversal portion. As a matter of fact, in actual practice or during operation of the improved traverse roller described herein, it has been found that the yarn jumps from the rapid reversal portion to a point approximately five inches there behind. Thus, it is not absolutely essential that guide wires 20 extend the full 180 degrees around the roller although such might be desirable when operating the roller at lower speeds of rotation.

Figure 4, which is a section taken substantially along the high point of one of the rapid reversal portions 14, illustrates the relative disposition of the axial guide pin 17, the radial guide pin 15 and one of the guide wires 20. It can be seen that radial pin 15 is locked against dislocation due to centrifugal force by guide wire 20, which wire is securely held in position by the projecting lip portions 21, 22, the struck-over ends 23 and adhesive means. The axial pin 17 is locked into position by the ends thereof which protrude into the inner and outer walls of the groove, as is evident from the drawings.

Example

It was found that the above described invention operated very successfully when applied to a known die-cast aluminum traverse roller. This roller was of the hollow drum type such as that shown in Figure 2, 13½ inches in diameter and with a continuous helical groove formed in the outer surface thereof. The groove had a depth of 1 inch and a width ½ inch, and the traverse stroke was 2¾ inches.

To this traverse roller was added, at each of the points of rapid reversal, two $\frac{3}{16}$ inch diameter radial pins and two $\frac{3}{16}$ inch diameter axial pins, the pins being made from wear-resistant "Alsimag." The guide wires were constructed of $\frac{1}{8}$ inch diameter chrome plated steel of a length to extend up to 180° around the traverse roller, beginning approximately two inches behind one radial guide pin and extending in the direction of rotation to a point approximately four inches from the other radial guide pin. The ends of the guide wires projected through

suitable apertures provided in the roll and were struck over, as explained hereinabove, to secure the wires in the channels. Cement from the epoxy class was used to facilitate this mounting. The average yarn speed was 900 meters per minute and the direction of rotation of the roller 10 was counter to the rotation of the take-up bobbin, as shown by the arrows in Figure 1. The package was surface driven from a conventional drive roller, not illustrated in the drawing.

It has been found that a traverse roller of the type described hereinabove has a useful life many times longer than that of known rollers. Moreover, the maintenance on such a roller is extremely simplified and made more economical. The guide pins and wires may be easily replaced if worn or broken without repairing the surface of the roller or without the use of expensive machinery and skilled operators. Moreover, the "down time" for such repairs is greatly reduced from that previously required. The overall result of the foregoing is that much more compact and uniform packages are produced from the traverse roller for longer periods of operation.

It is understood that the description of the above embodiment is for purposes of illustration and is not intended to limit the scope of this invention except to the extent defined in the claims.

What is claimed is:

1. A yarn traversing roll comprising a rotatable cylinder having a helical cam groove in the outer surface thereof, said groove having two rapid reversing sections, and a wear-resistant member embedded in the outer edge of said groove and extending from a trailing edge of one rapid reversing section through the other rapid reversing section, said wear-resistant member projecting from said outer edge into yarn-contacting position.

2. A yarn traversing roll as set forth in claim 1 wherein said wear-resistant member is formed of chrome plated steel wire and extends approximately 180° around the rotatable cylinder.

3. A yarn traversing roll comprising a rotatable cylinder having an endless helical cam groove in the outer surface thereof, at least one wear-resistant yarn-contacting guide extending radially of said cylinder along one

wall of said groove, at least one wear-resistant yarn-contacting guide extending axially of said cylinder adjacent the radial guide and along the bottom surface of said groove, means defining successive channels in alternate outer edge portions of said groove, and a wear-resistant yarn-contacting member positioned within each of said channels.

4. A yarn traversing roll comprising a rotatable cylinder having an endless helical cam groove in the outer surface thereof, said groove having first and second reversing sections, a wear-resistant yarn-contacting guide extending radially of said cylinder along one wall of said groove at each of said reversing sections, a wear-resistant yarn-contacting guide extending axially of the cylinders adjacent to the radial guide and along the bottom surface of said groove at each of said reversing sections, means defining a first channel in one outer edge portion of said groove and extending longitudinally thereof from the trailing side of said first reversing section substantially through the second reversing section, a wear-resistant yarn-contacting member positioned within said first channel, means defining a second channel in the other outer edge of said groove and extending longitudinally thereof from the trailing side of said second reversing section substantially through the first reversing section, and a wear-resistant yarn-contacting member positioned within said second channel.
5. A yarn traversing roll comprising a rotatable cylinder having an endless helical cam groove in the outer surface thereof, means defining successive channels in alternate outer edge portions of said groove, and a wear-resistant member secured within each of said channels and projecting therefrom into yarn-contacting position, said member extending at most 180° around the cylinder.
